(57) **CLAIM**

The ornamental design for the security tag housing, as shown and described.

DESCRIPTION

FIG. 1 is a perspective view of the security tag housing; FIG. 2 is a top view of the security tag housing of FIG. 1; FIG. 3 is a bottom view of the security tag housing of FIG. 1;

FIG. 4 is a side view of the security tag housing of FIG. 1; FIG. 5 is a side view of the security tag housing of FIG. 1 showing the side opposite that shown in FIG. 4;

FIG. 6 is a front view of the security tag housing of FIG. 1; and,

FIG. 7 is a rear view of the security tag housing of FIG. 1. The broken lines form no part of the claimed design. The dash-dot lines depict portions of the security tag housing that forms no part of the claimed design. The dash-dot lines in FIG. 3 are boundary lines such that the area bounded thereby forms no part of the claimed design.
